FLOOR CLEANSING DEVICE

Ernest R. Ballantyne, Columbus, Ohio, assignor to Wayne Chemical Company, a corporation of Ohio
Filed May 13, 1963, Ser. No. 280,034
3 Claims. (Cl. 15—526)

This application relates to and is a continuation-in-part of my co-pending application, Serial Number 123,800, filed June 13, 1961, for Floor Cleansing Device, now Patent No. 3,114,922.

This invention relates generally to floor covering cleansing devices, and specifically to a new and improved method and means of controlling the dispensing of the cleansing agent on the material to be cleansed to facilitate the brush action in the cleansing device.

In my earlier co-pending application, I disclosed the unique principle of a self-contained floor cleansing device for converting the detergent material to suds or foam prior to application to the floor covering. By only applying foam to the material to be cleansed, the material remains comparatively dry thereby removing the danger of shrinkage and rapid subsequent soiling. Also, a uniform application of cleanser is applied and only the detergent that is used is dispensed.

To utilize this basic principle, I have disclosed in my earlier co-pending application apparatus that generally comprises a detergent storage tank, a pump means for converting the detergent to foam and a foam applicator. The pump means is actuated by the movement of the floor contacting mechanism. An alternate arrangement is also shown and described wherein the pump for the foam generator is electrically driven in order to generate rapid and large amounts of foam. The instant application is directed to the electrically driven pump for the foam generator.

Accordingly, it is a general object of my present invention to provide a new and improved floor cleansing device that utilizes the basic principle of applying only detergent foam to the material to be cleansed.

It is a further object of my invention to provide a floor cleansing device with an improved air injection mechanism that is electrically driven.

It is another object of my invention to provide an electrically driven pump for a foam generator having an adjustable air-to-fluid ratio.

It is still another object of my invention to provide a floor cleansing device that is extremely rugged and yet simple in operation and inexpensive to manufacture.

Other objects and features of the present invention will become apparent from the following detailed description when taken in conjunction with the drawings in which:

FIG. 1 is an over-all illustration of a floor cleansing device utilizing the basic principle of a foam generator;

FIG. 2 is an over-all illustration of a preferred embodiment of my invention utilizing an electrically driven foam generator;

FIG. 3 is another embodiment of the invention utilizing an electrically driven foam generator;

FIG. 4 is a part-sectional view and part-schematic view of the electrically driven air injection mechanism incorporating the principles of the present invention generally shown in FIGS. 1 and 2;

FIG. 5 is a part-schematic and part-sectional view of an alternative arrangement of the electrically driven foam generator of the present invention;

FIG. 6 is a side view of the air and liquid shut off discs of FIG. 5;

FIG. 7 is a side view of the liquid and air control discs of FIG. 5;

2

FIG. 8 further illustrates the liquid and air control disc relative to the shut off position; and

FIG. 9 is another brush unit adaptable to the embodiment of FIG. 5.

Referring now specifically to FIG. 1, there is shown in perspective the basic embodiment of my present invention. The embodiment comprises a handle generally shown at 10 having supported thereon a liquid detergent storage tank 20, pump means 24 that may be activated by back-and-forth movement of the floor contacting mechanism shown generally at 30 or through the action of handle 15. As the foam or foaming lather is generated in the pump 24, it is transferred to the floor covering adjacent to the point of contact of the applicator brushes 14 and 16 and roller 18 for applying the foam to the floor covering.

In some instances where a considerably larger area is desired to be cleaned, it may be necessary to electrically drive the pump for the foam generator in order to generate a sufficient amount of foam. Also, since the greatest physical exertion in the use of the preferred embodiment would be in the brush contact, it may also be desirable to electrically drive the brushes. With reference to FIG. 4 there is shown electric motor 91 energized by electrical source 94. Connected to motor shaft 91a is a pulley 95 having a belt 92 tightly coupling pulley 93. The size of pulleys 95 and 93, of course, may be chosen to the appropriate gear ratio. Pulley 93 being fixedly connected to axle 31 drives both the pump shaft 38 and the two brushes 51 and 47 through the pulley and belt action described in relation with FIG. 4 above.

Referring to FIG. 2 there is illustrated the preferred embodiment of FIG. 4 with all of the moving parts and mechanical operation removed from view by the streamlined housings 39 and 32. Also shown in this embodiment is the handle 46 that also serves the purpose of an electrical switch by the up-and-down movement and as a rheostat to control the speed of the electrical drive. Also for convenience, there is attached to handle 52 retaining means 96 and 96a for coiling of the electrical wire 94.

With reference to FIG. 3 there is shown another embodiment that adapts the principles of my invention to another type of cleaning operation. In some instances, the material to be cleaned, such as upholstery, drapes, and car seats, would not be reached by a floor type of cleaning device. Accordingly, there is shown in FIG. 3 a portable type of cleaner that could be utilized for all types of cleaning operations. In more detail, the principle of operation is similar to that of FIG. 1, except that the foam generator and/or the brushes are power driven. Further, the entire mechanism is housed into a portable device. That is, housing 102 covers the entire mechanism and is secured thereto by fastener 103. To facilitate the hand operation, handle 101 is attached to the housing 102.

In an alternative arrangement of the apparatus of the present invention, an electrical motor driven compressor unit is substituted for the air pump unit described hereinafore. The basic principle of operation is substantially the same as described above. However, in this embodiment the foam scrubber may readily be ruggedized and consequently made suitable for commercial and continual use type of applications.

Referring now to FIG. 5, there is shown a preferred embodiment of the present invention utilizing an electrical motor driven compressor type of foam generator. More specifically, the compressor unit 110 is a commercially available compressor and per se does not form a part of the invention. The electrically driven compressor 110 via outlet 111 pressurizes the liquid detergent tank 120. The pressure in tank 120 causes the liquid 117 to flow via rigid tube 116 and thence flexible tube 114. The air

pressure in tank 120, also seeking a low pressure area, will flow through the outlet 126 and then through tube 115. The liquid fluid and air is transported through the tubing 114 and 115 to the foam generator unit 12.

The foam generating unit 12 of this embodiment comprises a cylindrical housing 11 having at its one end 13 an entry for the air and liquid tubings 114 and 115. Permanently fixed as walls in the housing 11 are discs 21 and 22 in continuous contact with the inner wall 26 of the housing. Also pivotally secured by pin 25 to discs 21 and 22 is a third disc 23 of oblong shape. Referring to FIG. 6, it is seen the discs 21, 22 and 23 comprise passages 21a and 21b, 22a and 22b, and 23a and 23b. When the discs are positioned within the housing, their respective passages are in direct line with each other. Fixed to disc 21 are rigid tubings 27 and 28 of just smaller diameter than the inside diameter of the tubings 114 and 115; and hence adapted to receive these tubings. Thusly there is communicated air and liquid detergent to the mixing unit. Since the passages in the discs are in direct line, it is seen that the air and detergent are permitted to pass freely therethrough. The tubing 28 does not extend beyond the first disc 21 and in this embodiment terminates in air chamber 30 whereas the liquid tubing 27 passes through air chamber 30 and into the mixing chamber.

The air build up in air chamber 30 is also forced around the tubing 27, into the nozzle 34 and thereafter through the ports 51 and 51a located on either side of the nozzle 34. The liquid in tubing 27 passes through the chamber 30 and is exhausted directly into the nozzle 34 from the orifice 52. The air entering the mixing area 14 causes the air to mix with the fluid. The liquid and air strike the inner walls of the outer housing 36 and are forced through the port 38 in a fine spray. This spray is then forced through a fine mesh screen 42 and is converted into a foam. The foam is then passed into foam transfer means 33 and then to the brush 35 where it may be imparted to the workpiece.

In order to provide a shut off for the liquid and/or air such as when the workpiece may become saturated and pressure is still in the tank 117, the disc 23 may be pivoted such as with lever 45 to one side or the other thereby disaligning the passages 21a and 21b with 22a and 22b. The oblong shape of disc 23 with the pin 25 are merely illustrative of the pivoting of the center disc relative to the outside discs. In actual practice, the disc 23 will be round and in rubbing contact with the surface of discs 21 and 23 and in edge contact with the inside wall of the housing. Material such as trade named "Teflon" would be suitable for the disc material.

The outside tube 113 is of somewhat smaller length than the inner tubings 114 and 115. Thusly, when tubing 113 is fixed to the tank at 125 and the housing 126, the inner tubings are permitted play. Also, the wear through friction with the workpiece will be borne by the outer tubing 113.

The brush 35, as shown in FIG. 5, is adapted for use on a workpiece such as upholstery. In order to adapt the same scrubbing unit to a floor piece operation, the brush 35 may be removed by disengaging the pin and lock arrangement 17 and inserting therein an elongated type of handle and brush as shown in FIG. 9.

In actual practice of the cleansing device, it has been found that the ratio of air to liquid is not a constant factor for the cleansing of all types of carpets. More precisely, in cleaning a heavy pile carpet or rug, a dry foam would not be sufficiently penetrating to clean the entire pile. On the other hand, in cleaning a relatively smooth carpet, a wet foam would not be necessary. Accordingly, to more generally apply the foam generated cleansing device, it has been found expedient to devise means to vary the relative wetness of the foam.

In another instance—with a constant ratio of air-to-liquid—it has been found that after extended usage of the cleansing device, that dry detergent will build up on

the fluid tube nozzle and specifically around the orifice 38. This build-up would impede the amount of liquid expelled and consequently vary the air-to-liquid ratio for proper spraying action.

In order to overcome the above dry detergent build-up, and also to extend the applicability of the floor cleansing device, there is provided in the present invention a variable nozzle. This improvement permits the operator to control the wetness of the foam, i.e., the air-to-liquid ratio. More specifically, in the preferred embodiment of FIG. 5, spray nozzle 36 is threaded onto tube 34. To control the mixture of air-to-liquid, the nozzle 36 is adjusted forward or back. That is, when nozzle 36 is screwed back against fluid tube nozzle 34, it cuts off air flow from air ports 51 and 51a and fluid only is dispensed. As nozzle 36 is screwed out, an increasing amount of air escapes through ports 51 and 51a, thus increasing the amount of air mixing with the liquid from orifice 52. It is apparent that by controlling the amount of air to be mixed with the liquid detergent, the spray expelled from port 38 will be wetter or drier. Consequently, as this spray strikes the screen 42, there will emerge therefrom a foam of controlled wetness.

In order to manually adjust the degree of wetness, the nozzle 36 is permanently fastened to the outer housing 40. Secured to housing 40 is the adjusting lever 44 in passing through the opening 43. It is readily seen that by moving the lever 44 in one direction or another, the nozzle 36 is screwed in or out to the amount desired.

An alternative method and means of varying the wetness of the foam is to control the amount of liquid detergent relative to air that is permitted to enter the nozzle shown in FIGS. 7 and 8. The discs 21, 22, and 23 may be utilized, in addition to being an on-off control, as a ratio of air-to-liquid control. This may be accomplished by attenuating the passages 21a and 23a in the disc 22 of FIG. 5 to such as 23c and 23d shown in FIG. 7. As the disc 22 would be pivoted from left to right—assuming an initial off position as shown—the air entering the nozzle would be of much greater capacity than liquid. As the movement continues, the amount of air would decrease, whereas the amount of liquid detergent would increase.

The housing 11 includes a cross-slot 48 to permit rotation of the disc 23 by the lever 45. The housing may further include a graduation thereon having relative indications as illustrated in FIG. 8 indicating the off position and the dry-to-wet foam that may be desired.

Again in actual practice, since the on-off will be manipulated many times during any one cleaning operation, whereas the wet-to-dry ratio will be kept constant after it is once set, it would be desirable to include separate discs for the on-off control and the ratio control.

Although I have shown a certain and specific embodiment, it is understood that departures may be had thereto within the scope of my invention.

What is claimed is:

1. A cleansing device of the kind described comprising a housing including a workpiece contacting means; a liquid detergent storage tank in communication with said housing, air pressurizing means positioned adjacent to and also in communication with said liquid storage tank, electrical drive means for activating said air pressurizing means to pressurize said detergent storage tank, mixing means, said air pressure independently introducing said air and said liquid detergent into said mixing means, said mixing means combining said air and liquid detergent for converting said air and detergent to foam, and transfer means connected to said foam generator for transferring said foam to said workpiece; means for controlling the ratio of liquid detergent to air entering said mixing means, said control means including a first wall in said housing having a pair of passages therethrough, means connecting said air to one of said passages and means connecting said liquid detergent to the other of said passages, a second

wall in said housing, said second wall being rotatable relative to said first wall about an axis extending perpendicularly through their centers, a pair of passages in said second wall, said passages being of such shapes as to be partially aligned with the passages in said first wall while the second wall is rotated between a first and second position, the shape of said passages in said second wall providing a range of positions intermediate said two positions in which range the amount of liquid supplied to the mixing means varies from zero to a maximum flow while the amount of air supplied to the mixing means varies between a maximum and zero flow, both said flow variations being in direct proportion to the degree of rotation from said first position toward said second position.

2. A cleansing device of the kind described comprising a housing including a workpiece contacting means, a liquid detergent storage tank in communication with said housing, air pressurizing means positioned adjacent to and also in communication with said liquid storage tank, electrical drive means for activating said air pressurizing means to pressurize said detergent storage tank, mixing means, said air pressure forcing said liquid detergent to said mixing means, means also introducing said air into said mixing means, said mixing means combining said air and liquid detergent for converting said air and detergent to foam, and transfer means connected to said foam generator for transferring said foam to said workpiece; means for controlling the ratio of liquid detergent to air entering said mixing means including a first and second wall each having a pair of passages therethrough, said passages in the first of said walls in alignment with the passages in the second of said walls, means connecting said air to one of said passages in the first of said walls and connecting said detergent to the other of said passages in said first wall, a third wall in said housing, said third wall being rotatable relative to said first and second walls about an axis extending perpendicularly through their centers, a pair of passages in said third wall, said passages being of such shapes as to be partially aligned with the passages in said first and second walls while the third wall is rotated between a first and second position, the shape of said passages in said third wall providing a range of positions intermediate said two positions in which range the amount of liquid supplied to the mixing means varies

5 from zero to a maximum flow while the amount of air supplied to the mixing means varies between a maximum and zero flow, both said flow variations being in direct proportion to the degree of rotation from said first position toward said second position.

10 3. A cleansing device of the kind described comprising a housing including a workpiece contacting means; a liquid detergent storage tank in communication with said housing, air pump means positioned adjacent to and also in communication with said liquid storage tank, drive means for activating said air pump means, mixing means, said air pressure independently introducing said air and said liquid detergent into said mixing means, said mixing means combining said air and liquid detergent for converting said air and detergent to foam, and transfer means connected to said foam generator for transferring said foam to said workpiece; means for controlling the ratio of liquid detergent to air entering said mixing means, said control means including a first wall in said housing having a pair of passages therethrough, means connecting said air to one of said passages and means connecting said liquid detergent to the other of said passages, a second wall in said housing, said second wall being rotatable relative to said first wall about an axis extending perpendicularly through their centers, a pair of passages in said second wall providing a range of positions intermediate said two positions in which range the amount of liquid supplied to a mixing means varies from zero to a maximum flow while the amount of air supplied to the mixing means varies between a maximum and zero flow, both said flow variations being in direct proportion to the degree of rotation from said first position toward said second position.
